CLAIM

The ornamental design for a handheld cheese grater, as shown and described.

DESCRIPTION

FIG. 1 is a front perspective view of a handheld cheese grater showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a view of the open state of a handheld cheese grater; and,

FIG. 10 is an exploded view of a handheld cheese grater. The broken lines in the drawings illustrate the portions of the handheld cheese grater, which form no part of the claimed design.

1 Claim, 10 Drawing Sheets
